Primary Examiner — Melanie H Tung(74) *Attorney, Agent, or Firm* — NSIP Law(57) **CLAIM**

We claim the ornamental design for a display screen or portion thereof with graphical user interface, as shown and described.

DESCRIPTION

The sole FIGURE is a front view of a display screen or portion thereof with graphical user interface showing our new design.

The outer broken lines in the FIGURE depict a display screen or portion thereof and form no part of the claimed design. The remainder of the broken lines in the FIGURE depict portions of the graphical user interface that form no part of the claimed design.
